UNITED STATES PATENT OFFICE.

ROBERT B. WARDIN, OF PHILADELPHIA, PENNSYLVANIA.

DESIGN FOR THE HANDLE OF A KETTLE-COVER.

Specification forming part of Design No. 6,376, dated January 28, 1873.

To all whom it may concern:

Be it known that I, ROBERT B. WARDIN, of the city and county of Philadelphia, State of Pennsylvania, have invented a Design for the Handle of a Kettle-Cover, of which the following is a specification:

The nature of my design is fully represented in the accompanying photographic illustration, to which reference is made.

A represents the base, which is of the form of a mound, or somewhat pyramidal or conical. The face of the base may be scored or grooved, and from projections B on opposite portions of said base there rise leaves C, which are curved and curled, portions *a* of which are scalloped, and embrace the other portions *b*,

so that the upper terminations of the leaves are bifurcated or somewhat tulip-shaped; and from said terminations there rise scrolls D, which extend toward each other and are connected by a foil, E.

What I claim as my invention is—

The ornamental design for the handle of a kettle-cover, substantially as represented and described.

The above signed by me this 9th day of January, 1873.

R. B. WARDIN.
